UNITED STATES PATENT OFFICE

138,966

DESIGN FOR A TOY

Joseph E. Miano, New York, N. Y.

Application March 15, 1944, Serial No. 112,908

Term of patent 3½ years

(Cl. D34—15)

To all whom it may concern:

Be it known that I, Joseph E. Miano, a citizen of United States, residing at New York city, in the county of Bronx and State of New York, have invented a new, original, and ornamental Design for a Toy, of which the following is a specification, reference being had to the accompanying drawings, forming part thereof.

In the drawings:

Fig. 1 is a view in elevation, of one side of a toy showing my new design;

Fig. 2 is a view, in elevation, of the other side thereof;

Fig. 3 is a top plan view, and

Fig. 4 is an end view thereof.

I claim:

The ornamental design for a toy, substantially as shown.

JOSEPH E. MIANO.
